UNITED STATES PATENT OFFICE.

SIDNEY GITTNER, OF BROOKLYN, NEW YORK.

SAFETY-COCK FOR GAS-RANGES.

1,206,320.

Specification of Letters Patent. Patented Nov. 28, 1916.

Application filed March 9, 1916. Serial No. 83,065.

To all whom it may concern:

Be it known that I, SIDNEY GITTNER, a citizen of the United States, residing at 1770 Park Place, Brooklyn, in the county of 5 Kings and State of New York, have invented a new and useful Safety-Cock for Gas-Ranges, of which the following is a specification.

My invention relates to improvements in 10 safety cocks for gas ranges, and it consists in the novel features hereinafter more fully described.

The objects of my improvement are: First. To provide a safety cock for gas ranges, 15 which could not be opened by children or by brushing against it inadvertently thereby preventing accidents frequently due to the manipulation of the usual gas cocks in ranges by children. Second. To have the controlling means of the mechanism of the safety 20 cock for gas ranges hidden from view and inclosed by the plug of the gas cock. Third. To have said mechanism serve also as a means for regulating the amount of opening 25 of the gas cock. Fourth. To have the resistance to releasing the mechanism of the safety cock for gas ranges sufficiently great to be beyond the power of children to overcome it. Fifth. To have said safety cock for 30 gas ranges simple, durable and inexpensive. I attain these objects by the mechanism illustrated in the accompanying drawings or by any mechanical equivalent or obvious modification of the same.

35 In the drawings Figure 1 is a longitudinal vertical section by a plane passing through the axis of the seating of my safety cock for gas ranges. Fig. 2 is a plan of the seating of one form of my safety cock for gas ranges, with the plug removed, and showing a circular series of grooves or notches 31, 31, hereinafter described. Fig. 3 is an end elevation of my safety cock for gas ranges, looking toward the left in Fig. 1. Fig. 4 is 40 a horizontal section of the plug on the line C—D of Fig. 1 passing through the horizontal arm 25 of the bell crank lever 23 and the lower end 24^a of the push rod 24, hereinafter described. Fig. 5 is a plan of the seating of another form of my safety cock for gas 45 ranges with the spigot end broken away, and showing a ratchet 33 secured to the upper face of the seating instead of the series of grooves 31, shown in Figs. 1, 2 and 3. Fig. 6 is a side elevation of the form of my 50 safety gas cock shown in Fig. 5, with the ratchet 33 in place.

Similar numerals and letters refer to similar parts throughout the several views as follows:

55 11 is the seating of the safety cock; it is shown in Figs. 1, 2 and 3 as having on its upper face a circular series of grooves or notches 31, 31.

60 12 is the socket end of the seating and 13 is the corrugated spigot end of the seating, both of usual construction.

65 14 is the plug of the safety cock, the lower end of which is of the usual form; it is kept in place by the set screw 17 and 70 washer 18, located under the seating 11.

70 15 is the handle of the plug 14, formed in one with the knob 16 at the upper end of said plug 14.

75 19 is the gas passage through the plug 14; 20 is the gas passage through the seating 11; 21 is the end of said passage 20 through the spigot; it is shown in Figs. 1 and 3 as reduced in diameter.

80 22 is a round passage transversely through the plug 14 above the seating 11, which opening serves as a housing for part of the mechanism of my safety gas cock, as hereinafter described. This passage 22 may be conveniently formed by drilling a hole in a plug 85 of a standard gas cock.

85 23 is a bell crank lever having a vertical arm or click 23^a, the end of which is adapted to engage the grooves 31 in the form of my device shown in Figs. 1, 2 and 3, or the 90 ratchet 33 in the form of my device shown in Figs. 5 and 6; it also has a horizontal arm 25, which terminates in a fork pivotally connected by means of a pin 27 to the lower end 24^a of a vertical push rod 24, which passes 95 through a suitable vertical opening in the plug 14 and has a sliding fit therein. Said rod 24 terminates at its upper end in a head 30. 26 is the spindle, on which said bell crank lever 23 oscillates; it is journaled at 100 its two ends in the walls of said passage 22 of the plug 14, transversely thereto. 28 is an enlargement at the upper end of the vertical opening, through which said rod

- 24 passes; it may be formed by drilling a vertical hole in said knob 16 of the plug 14 of the gas cock. 29 is a compression spring located in said enlargement 28; it is shown 5 as encompassing the upper end of said rod 24, and abutting against the underside of the head 30 of said rod 24, thereby tending to raise said rod 24, and thereby acting upon said bell crank lever 23 in such a way as to 10 keep the end of the click 23^a in one of the notches or grooves 31 shown in Figs. 1, 2 and 3, or in contact with the ratchet 33, shown in Figs. 5 and 6, on the upper face of the seating 11, and thereby preventing the 15 turning of said plug 14. 32 are two apertures in the walls of said passage 22 of the plug 14, to allow the passing of the pin 27 therethrough when assembling the mechanism.
- 20 Both the spindle 26 and the pin 27 are shown as riveted over at their ends, to prevent their displacement.

The ratchet 33 is shown in Fig. 6 as having its teeth formed on the outer edge of an 25 annular plate, which may be secured to the upper face of the seating 11 either by soldering or in any other suitable manner.

The spaces between the teeth of the ratchet 33 can be milled out or formed in 30 any other manner; and I designate them in the claims as grooves, the same as the grooves or notches 31.

To release the click 23^a it is necessary 35 to depress the head 30 of the rod 24 against the direct pressure of the spring 29, without any leverage to assist in overcoming the resistance of said spring 29; it is evident, therefore, that a spring of a comparatively small size may offer a sufficiently 40 great resistance to be beyond the strength of a child to overcome it, and depress said rod 24.

Fig. 5 shows the ratchet 33 as consisting 45 of two pair of quadrants, with the teeth in each pair of quadrants inclined in opposite directions, and with a single groove or notch 31 at the meeting point of the pair of quadrants; each of these grooves 31 is situated above the middle point of the side of 50 the seating 11, and they correspond to the position of the click 23^a, when the gas cock is closed and the handle 15 of the plug 14 is at right angles to the position thereof shown in the drawings. It is evident that 55 with the form of my device, shown in Figs. 5 and 6, it will be necessary to press the head 30 of the rod 24 only for opening the gas cock; the inner edge of the click 23^a will pass over the teeth of the ratchet 33 when closing the gas cock. This is designed to enable a person to close the gas cock in a hurry, also to avoid touching the head 30 of the rod 24, which may be hot, when it is necessary to close the gas cock.

The head 30 is shown in the drawings as 65 having a smaller diameter than said enlarged opening 28, for the sake of clearness; but it can be formed so tight fitting and of such a shape as to appear like the top of the knob 16, without suggesting to children 70 that there is any mechanism underneath it to meddle with.

The passage 22 is shown in the drawings as extending through the entire thickness of the plug; but it may extend only part of 75 the way therethrough, if desired, to prevent children from putting their fingers thereinto through the open end, which may also be plugged, if desired.

The rod 24 may be located in the handle 80 15 of the plug, if desired, and its motion transmitted to the bell crank lever 23 by means of a suitable link and levers inclosed in said plug.

Many other changes could be made in the 85 design of my safety cock for gas ranges within the scope of my invention; as for example:—A tensile spring may be employed to act on the rod 24, which may be used as a pulling rod instead of a push rod. 90

In the form of my device, shown in Figs. 1, 2 and 3, the grooves or notches 31, instead of extending in a series through a complete circumference of a circle, as shown, may extend only through part of the circumference, 95 and the number of notches 31 may even be reduced to one, if desired; the grooves or notches 31 may also be formed in any convenient part of the seating other than the upper face thereof; the click 23^a may be 100 rigidly connected to the rod 24 by means of a suitable bar, instead of being pivoted to the plug 14 and having its horizontal arm pivotally connected to said rod 24.

In the form of my device shown in Figs. 105 5 and 6 only one or two of the quadrants of the ratchet 33 may be used, if desired. Also only some of the features of my device may be employed, thereby securing part of the advantages thereof.

I do not, therefore, restrict myself to the exact shape of my safety cock for gas ranges as shown in the drawings, but I intend to include also all mechanical equivalents and obvious modifications thereof.

What I claim as my invention, and desire to secure by Letters Patent is:

1. In a safety cock for gas ranges a seating, a plug, a pair of ratchets on said seating, the teeth in each of said ratchets being inclined in opposite directions, a single groove or notch at the meeting point of said ratchets, a click, pivotally connected to said plug and adapted to fit the grooves between the teeth of said ratchets and into said single groove or notch, a controlling rod slidably connected to said plug and operatively connected to said click, thereby keep-

ing said click in position in said grooves, and a means for resisting the motion of said rod in such a direction as to remove said click from said grooves.

2. In a safety cock for gas ranges a pair of ratchets having their teeth laterally extending and inclined in opposite directions,

a click, adapted to fit the grooves between the teeth of said ratchets, and a controlling means adapted to keep said click in position in said grooves, thereby allowing the closing of said gas cock and resisting the opening of said gas cock. 10

SIDNEY GITTLER.
